UNITED STATES PATENT OFFICE.

JOSEPH R. LOCKE, OF AMESBURY, MASSACHUSETTS.

VEHICLE-WHEEL.

SPECIFICATION forming part of Letters Patent No. 247,257, dated September 20, 1881.

Application filed July 15, 1881. (No model.)

To all whom it may concern:

Be it known that I, JOSEPH R. LOCKE, of the town of Amesbury, State of Massachusetts, have invented an Improvement in Wheels, of which the following is a specification.

This invention relates to improvements in wheels for vehicles; and it consists in forming or producing the spoke-holes in the felly or rim with a diameter greater in the transverse than in the longitudinal direction of the rim or felly with the spoke-tenons circular in cross-section, whereby the contact-pressure between the spoke-tenon and the walls of the spoke-hole is prevented from checking and splitting the felly adjacent to such hole, as will, by the aid of the annexed drawings, be hereinafter fully described, and specifically defined in the appended claim.

Figure 1 is an enlarged view showing a spoke-tenon in transverse section and a section of a felly in plan, and showing therein in an exaggerated degree my improvement. Fig. 2 shows, in side elevation, a machine for carrying my invention into practice. Fig. 3 is a detached front elevation of some of the parts shown in Fig. 2. Fig. 4 is a side elevation, showing a modification of the machine for carrying my invention into practice. Fig. 5 is a horizontal section taken through the front bearing of arbor *m*, as shown in Fig. 4, and also through its supporting-strap, and showing said arbor in plan.

In the manufacture as well as use of wheels for vehicles, and especially light wheels with bent rims, one of the most serious difficulties encountered has hitherto been the tendency of the rims to split adjacent to the spoke-holes therein; and many devices have been employed to prevent this difficulty—such as metallic couplings, rivets, and headless screws applied to the felloes; but after numerous attempts and protracted trials the use of all kinds of metallic fastenings at the junction of the spoke and felly have been almost universally abandoned; and to effect the desired result I have invented my said improvement in the construction of the wheel itself.

For the purpose of showing some means of practicing my said invention, I have embodied in said drawings the machine there represented, in which—

d represents the bed or top, which is supported by legs *c*. A boring-arbor, *m*, is journaled in bearings *n* *n'*, secured to said frame. A boring-bit, *l*, is secured in said arbor, and is thereby rotated either through the use of crank *o* or by a belt acting upon pulley *p*. A curved-faced pressure-block, *e*, is secured upon bed *d*, and a similar block, *f*, is pivoted to the lower end of the lower arm, *g*, of a toggle-joint, while the upper end of the upper arm thereof is pivoted to the overhead support *h*, said toggle-joint being actuated by treadle *j*, which is actuated by pressure upon foot-pad *k*, which treadle is pivoted in bed *d*, as shown, while its upper end is pivoted to rod *i*, which is connected with the meeting ends of said arms *g*, and by depressing said treadle by means of pad *k*, pressure is exerted upon felly *a* when placed between blocks *e* *f*, as is clearly shown in Fig. 3. When thus compressed the spoke-holes *c* are successively bored by bit *l*, as before stated, the hole being in such case formed circular, as shown at the left hand in Fig. 3; but when relieved from such pressure the expansion of the wood will enlarge such hole in a direction transverse to the axle line of the felly, as shown by the right-hand hole *c* in said Fig. 3.

In Fig. 4 the arbor *m* is shown as journaled at the rear end in the bearing *s*, pivoted in support *t*, and at the front end in bearing *v*, which is guided in support *x*, and receives a slight vertical reciprocating motion through connecting-rod *y*, which at its upper extremity is secured to said box *v*, and at its lower extremity is by straps *z* attached to eccentric *a'*, which is secured to and rotated by shaft *b'*, so that when arbor *m* and shaft *b'* are simultaneously rotated bit *l* will, by its consequent rotary and vertically-vibrating motion, cut a hole in felly *a* with a greater vertical than horizontal diameter, and this whether the felly is compressed between blocks *e* *f* or not; but if thus bored when so compressed, then, of course, the elongation or oval form of the hole *c* will be so much the greater.

In Fig. 1 the enlargement of hole *c* transversely to felly *a* is shown as exaggerated, in order to exemplify the pressure between the felly and tenon *b* in the longitudinal direction of the felly, and the decreased transverse

pressure of said tenon upon the felly, by which any desired degree of pressure between the two may be secured without danger of splitting, and yet prevent compression of the felly so as to bulge the same at the sides opposite the spokes.

The arbor *m* may be actuated lineally by means of angle-lever *c''*, which is pivoted at *d'*, and at its upper end is attached to said arbor.

- I claim as my invention—
As an improvement in carriage-wheels, the

combination of the spokes formed with the tenons *b*, circular in cross-section, and the rim *a*, having the spoke-holes *c* formed therein, with a diameter greater in the transverse than the 15 longitudinal line of the rim, substantially as specified.

JOSEPH R. LOCKE.
